UNITED STATES PATENT OFFICE.

ELMER E. WOODWARD, OF ROCKFORD, ILLINOIS.

GOVERNOR FOR WATER-WHEELS.

SPECIFICATION forming part of Letters Patent No. 679,353, dated July 30, 1901.

Application filed December 8, 1900. Serial No. 39,245. (No model.)

To all whom it may concern:

Be it known that I, ELMER E. WOODWARD, a citizen of the United States, residing at Rockford, in the county of Winnebago and State 5 of Illinois, have invented certain new and useful Improvements in Governors for Water-Wheels and other Motors, of which the following is a specification.

Governors of this class consist, essentially, 10 of mechanism (frequently in the form of a friction-clutch) for applying power to open or close the valve or gate which admits water to the water-wheel and of a device (usually a pair of centrifugal balls) for controlling the 15 operation of said mechanism. While such a governor works well in many cases, it is not as sensitive as desired where very hard working gates are to be controlled, especially with the friction type of governor, as too great a 20 change of speed is necessary to cause the centrifugal balls to bring sufficient pressure upon the friction-clutch to cause the latter to operate the valve or gate. With this class of 25 governor in order to have the mechanism act quickly it also is necessary to provide some kind of compensating device to check the movement of the governor when the gate has been opened or closed sufficiently to balance the change of load, and thus to prevent what 30 is known as "racing."

The object of this invention is therefore to provide an extremely sensitive controlling device for water-wheel governors which shall positively and powerfully engage the friction 35 or other clutch mechanism when the change of load requires the position of the gate to be altered; also, in connection therewith an improved form of compensating mechanism for arresting the movement of the governor when 40 the gate has been moved the required distance, but before the speed of the water-wheel has been returned to the normal rate.

In the embodiment herein shown of this invention a friction-disk governor having the 45 usual centrifugal balls or weights is suitably connected with the gate to operate the same. Two tappet-arms fixed on a saddle pivotally supported are adapted to engage opposite sides of a constantly-rotated cam, one or the 50 other of said arms being brought into contact with said cam by the raising or the lowering of the balls. The movement of said tappet-

arms produced by said cam throws the central and constantly-rotating friction-disk of the governor into contact with either one of 55 two corresponding disks to rotate one of said last-mentioned disks to open or close the gate. By means of a friction-disk and friction-wheel, the latter being mounted on an inclined screw-threaded shaft having a rotatable connection 60 with the gate-operating shaft, the cam before mentioned is raised and lowered by the movement of said gate-operating shaft, so that said cam is withdrawn from engagement with the tappet-arms before said engagement would 65 otherwise be broken by the action of the centrifugal balls.

In the accompanying drawings, Figure 1 is a side elevation of a governor embodying the features of my invention. Fig. 2 is a plan 70 view of the same, showing the controlling mechanism in section on dotted line 2 2 of Fig. 1. Fig. 3 is an end elevation of the governor. Fig. 4 is a side elevation of one of the tappet-arms secured to its supporting 75 saddle-block and the spring for holding the tappet-arms elevated. Fig. 5 is a plan view of the saddle-block, the tappet-arms, and their actuating cam-wheel. Fig. 6 is an elevation of the governor-spindle, showing the 80 means of connecting the centrifugal balls therewith.

Like letters of reference indicate corresponding parts throughout the several views.

In the construction of this governor I provide a supporting-frame A, having the bearings A¹ for the gate-operating shaft and similar bearings A² for the friction-disk shaft. An upright standard A³ for supporting the speed-regulator and the compensating mechanism is secured by any suitable means to the supporting-frame A and forms a part 85 thereof. At its upper end the standard A³ has a transverse top portion A⁴, one end of which is adapted to support the centrifugal 90 balls, and the other end is provided with one of the two vertically-aligned bearings A⁵. On the opposite side of the standard A³ two arms projecting therefrom have at their outer ends the vertically-aligned bearings A⁶. Two projecting clips A⁷ are secured to the supporting-frame adjacent to the friction-disk shaft, the purpose of which clips will be explained 95 later herein.

The gate-operating shaft B is connected in any suitable manner, as by means of the beveled gear B', with the vertical shaft B², which extends to the gate, and which latter by 5 means of the hand-wheel B³ is capable of independent manual operation. B⁴ is a bevel-gear fixed on the end of the shaft B, and B⁵ and B⁶ are spur-gears fixed on said shaft between the bearings A'.

- 10 The friction-disk shaft C is journaled in the bearings A² of the supporting-frame A. It extends parallel with the gate-operating shaft B and has between its bearings A² the sleeves C' and C², loosely mounted on said 15 shaft. These sleeves are provided with the annular flanges or collars C³ adjacent to the inner ends of the bearings A², the retaining-clips A⁷ of the supporting-frame A lying in contact with said annular flanges, and, holding 20 them against the inner faces of the journal-bearings A², prevent a movement of said sleeves lengthwise of the shaft C. The opposite ends of each of the sleeves C' and C² bear friction-disks C⁴ and C⁵, respectively, 25 each of said disks being rigidly fixed on the inner end of its supporting-sleeve. Midway between the friction-disk C⁴ and the annular collar C³ the sleeve C' bears the spur-pinion C⁶, rigidly mounted on said sleeve, the sleeve 30 C² being also provided with a spur-pinion C⁷ in a similar position. The spur-pinion C⁶ meshes directly with the spur-gear B⁵ and the pinion C⁷ with the gear B⁶ through the intermediate idler-gear C⁸, rotatably mounted on 35 the supporting-frame A. Outside of the supporting-frame the shaft C has the two collars C⁹ rigidly fixed on said shaft and between them the shipper-collar C¹⁰, loosely mounted on the shaft C. A double-faced friction-wheel 40 C¹¹ is rigidly mounted on the shaft C between the corresponding friction-disks C⁴ and C⁵, and shifting mechanism, to be later described, connected with the loose collar C¹⁰ is adapted to throw the friction-wheel C¹¹ into frictional 45 engagement with either one of the disks C⁴ and C⁵. When the shaft C is moved longitudinally in the direction to throw the friction-wheel C¹¹ into contact with the friction-disk C⁴, the gate-operating shaft B is rotated by 50 means of its spur-gear connection with the sleeve C', and when the shaft C is moved longitudinally so that the friction-wheel C¹¹ contacts the disks C⁵ the gate-operating shaft B is rotated in a contrary direction by means of 55 the pinion C⁷, the idler-pinion C⁸, and the spur-pinion B⁶ on the shaft B. The shaft C and the friction-wheel C¹¹ are constantly driven in the direction of the arrow on the latter (see Fig. 1) by a belt passing from any 60 convenient part of the mechanism over the pulley C¹².

The standard A³ for the controlling device has at its upper end the usual governor-head D, provided with centrifugal weights D', pivotally mounted thereon and connected in the usual manner with the governor-spindle D² within the tubular governor-shaft D³. The

governor-shaft D³ is rotated by the bevel-gears D⁴ through the pulley D⁵. The governor-spindle D² rests at its lower end upon the saddle-block D⁶, and this block is carried upon the horizontally-pivoted arm D⁷ of the bracket D⁸. This bracket is fixed on the upper end of the vertical shaft E, which also carries at its lower end the shipping-fork E', fixed to said shaft E, and having, by means of the pins E², an engagement with the loose collar C¹⁰ of the shaft C. It will thus be seen that the oscillation of the vertical shaft E produces, by means of said connection, a longitudinal movement of the shaft C sufficient to move the friction-wheel C¹¹ into contact with either one of the friction-disks C⁴ and C⁵. The arm D⁷ rests upon the downwardly-extending pin E³, which pin extends through 80 an opening E⁴ in the bracket D⁸ and is surrounded below said bracket by the helical extension-spring E⁵. A hollow stud E⁶, threaded to correspond with the pitch of the spring, has a tubular stem E⁷, screw-threaded to correspond with the internally-threaded opening E⁴, said stem being intended to secure the upper end of the spring to the bracket D⁸. The lower end of said pin E³ is screw-threaded and has the wing-head E⁸ for turning said 95 pin. A stud E⁹, externally threaded to correspond with the pitch of the spring E⁵, is also internally screw-threaded to receive the pin E³. This stud holds the lower end of said spring E⁵ and causes it to be extended by a 100 downward pressure upon the pin E³.

A vertical shaft F, capable of a longitudinal movement, is mounted in the bearings A⁵ of the standard A³ and has fixed on its upper end the pulley F', over which the belt F² runs from the governor-shaft D³ to the vertical shaft F. The lower end of the vertical shaft F carries the friction-disk F³, and midway between the bearings A⁵ has the cam-wheel F⁴, also fixed on said shaft F. This 110 cam-wheel has a cam-scroll F⁵ upon each its upper and its under face, which scroll extends from a point near the center to the periphery of the cam.

Tappet-arms G and G' have a rigid connection with the saddle-block D⁶, one being secured to the upper face of said block, near one end thereof, and the other arm to the lower face of the block, on the opposite end thereof. The outer end of each of these tappet-arms has a transversely-sliding tappet G², and in a groove cut transversely in said tappet the free end of a flat spring G³ rests. The other end of this spring is secured to the outer side of the tappet-arm by means of the clamp G⁴, the tendency of the spring being to lie in contact with the tappet-arm and hold the tappet inward. The length of said springs is adjusted by changing the position of the clamp G⁴. The tappets G² are adapted to engage the cam-scrolls F⁵ and ride thereon as the cam-wheel is rotated. The scrolls move the tappets outward against the action of their springs G³, said springs cushioning the

pressure of the cam-scrolls F^5 upon the tappets G^2 .

A bracket H , in yoke form, is secured to the side of the standard A^3 and supports in 5 the bearing-blocks H' the inclined shaft H^2 , provided with a left-hand thread. Collars H^8 , provided with the notches H^4 , are fixed on said shaft H^2 and provide means for stopping the travel of the friction-wheel H^5 , 10 mounted on said shaft, the hub of said wheel being internally screw-threaded to correspond with the screw-threads upon the shaft H^2 . Said hub is also provided with projections H^6 , adapted to engage the notches H^4 of the 15 collars H^8 to limit the movement of said friction-wheel H^5 longitudinally of the shaft H^2 . The periphery of the friction-wheel H^5 supports the friction-disk F^3 . The shaft H^2 bears at one of its ends the bevel-gears H^7 , adapted 20 to mesh with the corresponding gear B^4 , so that the shaft H^2 is rotated whenever motion is imparted to the gate-shaft B .

In operation the gate is opened by means of the hand-wheel B^3 , turning the shaft B^2 in 25 the direction of the arrow in Fig. 1. A belt is passed over the pulley C^{12} to communicate motion from any moving part of the machinery to the shaft C . Rotary motion is also imparted to the governor-head by a belt passing 30 over the pulley D^5 from any rotating part of the machinery, and the centrifugal balls are actuated. The shaft F is constantly revolved by means of the belt F^2 , passing over the pulley F^4 and the tubular shaft D^3 of the 35 governor. The friction-wheel H^5 will be turned upon the threaded shaft H^2 by the friction-disk F^3 until said wheel is fed to the center of said disk, where it will stand until the gate-operating shaft B is rotated. As the 40 speed of the machinery increases above the normal rate the centrifugal balls D' fly farther outward from their supporting-shaft D^3 , pushing downward upon the governor-spindle D^2 . The end of this spindle resting upon the saddle-block D^6 causes the block to be depressed, 45 pushing the pin E^8 downward within the helical spring E^5 and extending the latter. The tappet-arms G and G' being rigidly secured to the saddle-block are likewise depressed, 50 the upper arm G' being pushed downward until the tappet G^2 in its outer end is brought into contact with the cam-scroll F^5 on the upper surface of the cam F^4 . This cam-scroll throws the tappet-arm G' outward, turning 55 the saddle-block and its supporting-arm with the oscillatory shaft E , and by means of the shifting-fork E' , connecting the shaft E with the shaft C , moves the latter shaft longitudinally in its bearings from right to left, 60 Fig. 2. The double-face friction-wheel C^{11} is thereby thrown into contact with the friction-disk C^4 . The disk C^4 is thus caused to rotate with the friction-wheel C^{11} . The spur-pinion C^6 is turned, meshing with and rotating the 65 spur-gear B^5 , revolving the shaft B , and turning the vertical shaft B^2 in a direction contrary to that indicated by the arrows on said

shaft in the drawings. The rotation just described of the shaft B was communicated by means of the bevel-pinion H^7 to the inclined 70 screw-threaded shaft H^2 , and the friction-wheel H^5 was fed downward upon said inclined shaft by means of its screw-thread engagement therewith. This downward movement of the friction-wheel H^5 lowered the 75 friction-disk F^3 and its shaft F , withdrawing the cam-wheel F^4 from engagement with the tappet G^2 of the tappet-arm G . As soon as the tappet-arm is withdrawn from its engagement with the scroll-surface of the cam by 80 the movement of the cam or the tappet-arm the friction-wheel C^{11} is free from its contact with the disk C^4 , and the rotation imparted to the shaft B is therefore suspended. If load is added to the water-wheel, the rate 85 of rotary motion of the balls D' is diminished and said balls descend, raising the governor-spindle D^2 and permitting the helical spring E^5 to throw the tappet-arm G upward, so that its tappet G^2 engages with the lower cam- 90 scroll of the cam-wheel F^4 . The rotation of the cam-wheel throws the tappet-arm G' outward, oscillating the shaft F , and by means of the fork E' shifts the shaft C longitudinally within its bearings. This longitudinal 95 movement of the shaft C throws the double-face friction-wheel C^{11} into contact with the friction-disk C^5 , causing the said disks C^{11} and C^5 to rotate together. Rotary motion is thus imparted by means of the pinion C^7 , the 100 idler-pinion C^8 , and the spur-gear B^6 to the shaft B , rotating said shaft and turning the vertical gate-operating shaft in a direction to open the gate, as indicated by the arrow in Fig. 1. The rotation thus imparted to 105 the shaft B is communicated to the inclined screw-threaded shaft H^2 , said shaft being turned in a direction contrary to that indicated by the arrow on the bevel-pinion B^4 , Fig. 1. As a consequence the friction-wheel 110 H^5 was fed upward on the screw-threads of said shaft, raising the cam F^4 out of engagement with the tappet G^2 of the tappet-arm G , permitting the friction-wheel C^{11} to release 115 its engagement with the friction-disk C^5 , thus stopping the rotation of the shaft B , and consequently the movement of the gate.

From the foregoing description it will be seen that the position of the centrifugal balls determines the movement of the gate, while 120 the friction-wheel H^5 and disk F^3 constitute a part of the mechanism that controls the action of said centrifugal balls. The friction-wheel H^5 bears normally upon the center of the constantly-rotating disk F^3 , and consequently receives no motion therefrom. Any movement of the gate-operating shaft raises or lowers the cam-wheel F^4 , and if that movement is sufficiently great the cam-wheel F^4 is moved away from the tappet-arm with which 125 it was in engagement. The action of the device thus is to check the movement of the gate in either direction before it otherwise 130 would be stopped by the action of the balls.

If the stopping of the gate were deferred until it was accomplished by the action of the balls, it would stop only after the normal speed of the machinery had been reached and passed. This would produce the so-called "racing," which it is one of the objects of this invention to avoid.

I claim as my invention—

1. In a water-wheel governor, in combination, a valve-operating means; and a controlling mechanism therefor, which controlling mechanism comprises a speed-regulator, a cam, and means adapted to be actuated by said cam, to assist the speed-regulator in controlling the valve.

2. In a water-wheel governor, in combination, a valve-operating means; and a controlling mechanism therefor, which controlling mechanism comprises a speed-regulator, a cam, and a tappet for engaging said cam.

3. In a water-wheel governor, in combination, a valve-operating means; and a controlling mechanism therefor, which controlling mechanism comprises a speed-regulator and a compensating mechanism, the latter comprising a cam and a tappet.

4. In a water-wheel governor, in combination, a valve-operating means; and a controlling mechanism therefor, which mechanism comprises a speed-regulator, a cam, and tappets therefor, and a compensating device actuated by the valve-operating means, adapted to assist the speed-regulator to actuate the valve-operating means.

5. In a water-wheel governor, in combination, a valve-operating means; and a controlling mechanism therefor, which mechanism comprises a speed-regulator and a compensating device, said compensating device comprising a cam and tappets and a device actuated by the valve-operating means adapted to bodily move the cam.

6. In a water-wheel governor, in combination, a clutch adapted to operate the power-valve; a tappet-arm adapted to operate said clutch; a rotatable cam; and a speed-regulator adapted to move the tappet-arm with relation to said cam.

7. In a water-wheel governor, in combination, a valve-operating means; and a controlling mechanism for the valve-operating means, said controlling mechanism comprising a speed-regulator, a cam and tappets, and a compensating device, the latter actuated by the valve-operating means and adapted to assist the speed-regulator in controlling the valve.

8. In a water-wheel governor, in combination, a speed-regulator; a valve-operating means controlled by the speed-regulator; and a compensating device actuated by the valve-operating means, and adapted to assist the speed-regulator in controlling the valve, which compensating device comprises a rotatable cam, tappets, and means actuated by the valve-operating means for bodily moving said cam and for rotating it.

9. In a water-wheel governor, in combination, a valve-operating means; a speed-regulator; and a compensating device actuated by the valve-operating means, the latter adapted to assist the speed-regulator in controlling the valve, which compensating device comprises a cam and tappets, a screw-threaded shaft, a friction-wheel having a screw-thread engagement with said shaft, a friction-disk for the friction-wheel, said screw-threaded shaft being placed at an angle with said disk, and means for rotating said screw-threaded disk with the valve-operating means.

10. In a water-wheel governor, in combination, a speed-regulator; a valve-operating means controlled by the speed-regulator; and a compensating mechanism comprising a cam, a cam-shaft, and tappets, also a screw-threaded shaft, a friction-wheel having a screw-thread engagement with said shaft, a friction-disk for the friction-wheel, which disk is fixed on said cam-shaft, the screw-threaded shaft being placed at an angle with said disk, and means for rotating said screw-threaded shaft with the valve-operating means.

11. In a water-wheel governor, in combination, a speed-regulator; a valve-operating means controlled by the speed-regulator; and a compensating mechanism comprising a cam, tappet-arms, an inclined screw-threaded shaft, a friction-wheel on said shaft, a friction-disk for said friction-wheel, and means for rotating said shaft when the power-valve is operated, to move said cam and assist the speed-regulator to release said mechanism.

12. In a water-wheel governor, in combination, a speed-regulator; two friction-disks for operating a power-valve; a friction-wheel for said disks; a tappet-arm adapted to move said friction-wheel into contact with either one of said friction-disks; a cam for moving said tappet-arm; and means for moving said cam bodily to assist the speed-regulator in controlling the power-valve.

13. In a water-wheel governor, in combination, a speed-regulator; two friction-disks for operating a power-valve; a friction-wheel for said disks; a tappet-arm adapted to move said friction-wheel into contact with either one of said friction-disks; a cam for moving said tappet-arm; an inclined screw-threaded shaft; a friction-wheel for said shaft; a friction-disk; and means for rotating said screw-threaded shaft when the power-valve is operated, to withdraw said cam from engagement with said tappet-arm.

14. In a water-wheel governor, in combination, a speed-regulator; two friction-disks for operating a power-valve; a constantly-rotated friction-wheel between said disks, capable of being placed in engagement with either one of said disks; a tappet-arm adapted to move said friction-wheel; a cam for moving said arm; a shaft for said cam; a friction-disk on said shaft; a screw-threaded shaft placed at an angle with the face of said last-mentioned friction-disk; a friction-wheel for said screw-

threaded shaft, adapted to engage said friction-disk; and means for rotating the screw-threaded shaft when the power-valve is operated, to withdraw said cam from engagement with said tappet-arm.

15. In a water-wheel governor, in combination, a speed-regulator; two friction-disks for operating a power-valve; a constantly-rotated friction-wheel between said disks, capable of being placed in engagement with either one of the disks; two tappet-arms adapted to move said friction-wheel; a cam for engaging said tappet-arms; a shaft for said cam; a friction-disk on said shaft; a screw-threaded shaft 15 placed at an angle with the face of said last-mentioned friction-disk; a friction-wheel for said screw-threaded shaft, adapted to engage said friction-disk; a gate-operating shaft; and a rotatable connection between the first-mentioned friction-disks and said gate-operating shaft, and between the screw-threaded shaft and said gate-operating shaft.

16. In a water-wheel governor, in combination, a speed-regulator; a friction-disk shaft; two friction-disks loosely mounted on said shaft; a friction-wheel fixed on said shaft between said friction-disks; a gate-operating shaft; a rotatable connection between one of said friction-disks and said gate-operating shaft, to rotate the shaft in one direction; a rotatable connection between the other friction-disk and the gate-operating shaft, to rotate the said shaft in a contrary direction; tappet-arms for moving the friction-disk shaft 35 to throw the friction-wheel into engagement with either one of said friction-disks; a cam for engaging said tappet-arms; a shaft for said cam; a friction-disk on said shaft; a friction-wheel having contact with said fric-

tion-disk; an inclined screw-threaded shaft 15 for said friction-wheel; and means for rotating the screw-threaded shaft when the power-valve is operated, to raise or lower the cam from engagement with the tappet-arms.

17. In a water-wheel governor, in combination, a shaft for operating a power-valve; a speed-regulator; a friction-disk shaft; two friction-disks loosely mounted on said shaft; a friction-wheel between said friction-disks, fixed on said shaft; a spur-gear connection 45 between one of said friction-disks and the shaft for operating the power-valve, to rotate said shaft in one direction; a similar connection between the other friction-disk and said shaft, to rotate said shaft in a contrary direction; 50 a shipping device for throwing the friction-wheel into contact with either one of said friction-disks; a supporting-shaft for the shipping device; a bracket at the upper end of said shipping device; an arm pivotally 55 mounted on said bracket; a saddle on said arm; two tappet-arms fixed with relation to said saddle; a spindle for the speed-regulator, the lower end of which spindle rests upon said saddle; a spring for holding the saddle 60 elevated; a cam between the outer ends of said tappet-arms; a shaft for said cam; a friction-disk on said shaft; a friction-wheel for said disk; a screw-threaded shaft for said friction-wheel, which said screw-threaded 65 shaft is inclined with relation to the bearing-face of its friction-disk; and a gear connection between the power-valve-operating shaft and the inclined screw-threaded shaft.

ELMER E. WOODWARD.
